UNITED STATES PATENT OFFICE.

EARL ROY FOUST, OF FLANDREAU, SOUTH DAKOTA.

MITER-BOX.

1,147,496.

Specification of Letters Patent. Patented July 20, 1915.

Application filed March 25, 1914. Serial No. 827,190.

To all whom it may concern:

Be it known that I, EARL ROY FOUST, a citizen of the United States, residing at Flandreau, in the county of Moody and State of South Dakota, have invented certain new and useful Improvements in Miter-Boxes, of which the following is a specification, reference being had to the accompanying drawings.

10 This invention relates to certain improvements in miter boxes and has relation more particularly to a device of this general character wherein the saw guide or frame is capable of adjustment to produce the required 15 site angles; and the object of the invention is to provide a device of this general character having novel and improved means whereby the saw guide or frame may be effectively maintained in its various adjustments and wherein the saw proper may be 20 adjusted with convenience and facility relative to the work, as the necessities of practice may require.

The invention consists in the details of 25 construction and in the combination and arrangement of the several parts of my improved miter box whereby certain important advantages are attained and the device is rendered simpler, less expensive and otherwise 30 more convenient and advantageous for use, all as will be hereinafter more fully set forth.

The novel features of the invention will be 35 carefully defined in the appended claims.

35 In order that my invention may be the better understood, I will now proceed to describe the same with reference to the accompanying drawings, wherein—

Figure 1 is a front elevational view of a 40 miter box constructed in accordance with my invention; Fig. 2 is a transverse vertical sectional view taken substantially through the center of Fig. 1; Fig. 3 is a view in top plan of the device as illustrated in Fig. 1, 45 with certain of the parts shown in section; Fig. 4 is a sectional view taken substantially on the line 4—4 of Fig. 3; Fig. 5 is a fragmentary view, partly in elevation and partly in section, illustrating the block herein included, at the side opposite to that shown in Fig. 2; Fig. 6 is a fragmentary sectional view illustrating in rear elevation the 50 depending disk herein included; and Fig. 7 is an enlarged fragmentary view, partly in

section and partly in elevation, illustrating 55 the means for maintaining the saw guide in an elevated position.

As disclosed in the accompanying drawings, 1 denotes a work table of any ordinary or preferred construction having its 60 intermediate portion cut away, as at 2, as is generally done in devices of this character, and 3 denotes the back plate also cut away, as indicated at 4, in a conventional manner. The side member 5 of the work table has 65 mounted thereon for rotation about a vertical axis, a bearing 6 while the opposite side member 7 of the work table is provided with a forwardly projected member 8, such member constituting a segment of a circle 70 circumscribed around the axial center of the bearing 6. Positioned below the member 8 and adapted to move relatively thereto is a block 9 provided at its rear face with an upstanding arm 9^a having its upper extremity angularly disposed and overlying the upper face of the member 8 and terminating in a bearing 10. By this arrangement, it will be seen that the arm 9^a serves as a supporting medium for the block 9. In order 80 to maintain the block against movement laterally of the member 8, I also provide said block 9 with an upstanding arm 9^b overlying the forward edge of the member 8, as is believed to be particularly shown in Fig. 85 2 of the accompanying drawings.

The bearings 6 and 10 have rotatably mounted therein, the lower connecting bar 11 of the tubular posts 12, such bar 11 being preferably circular in cross section and 90 adapted to have its upper portion substantially flush with the upper surface of the work table 1 when in operative position, and is provided with the longitudinal groove or recess 14 of predetermined depth adapted to accommodate the cutting edge or teeth of the saw in order to prevent such cutting edge or teeth from becoming injured after the work has been penetrated. The elongated recess or groove 14 is in alinement 95 with the slots 15 produced in the opposite walls of the posts 12, for purposes which are believed to be clearly obvious.

Telescopically engaged with each of the tubular posts 12 is a saw guide 17 having 105 intermediate its length the transverse opening or slot 16 through which the saw is adapted to be directed and in order that a

conventional saw may be employed, the upper extremity of such slot is enlarged, as indicated at 18.

The member 8 is adapted to determine the 5 horizontal angle at which the work is to be cut and in order that the angle may be determined with convenience and facility, I produce on the upper face of the member 8 the desired graduations, as indicated at 19, 10 while I produce on the under surface of the member 8 the transverse or radial grooves 20 in vertical alinement with the graduations 19 and which grooves are adapted to accommodate the peripheral portion of the 15 cam member 21 pivotally engaged with the block 9 at a point below the member 8 and which is adapted to so bind against the under surface of the rack 8 as to effectually hold or clamp the block 9 in its adjusted position.

In order to determine the requisite vertical angle of a cut, the bar 11 has depending therefrom in advance of but in close proximity to the member 8, the segmental disk 22 having the desired graduations 23 produced on the marginal portions thereof and having produced in its periphery in substantial register with the graduations 23 the notches or recesses 24 which are adapted to accommodate the peripheral portion of the cam member 25 operatively engaged with the face of the block 9 opposite to the face to which the cam 21 is connected. By this arrangement, it will be seen that the proper vertical adjustment of the saw will be effectively maintained. I also find it of advantage to have the lower forward portion of the block 9 provided with a recess or channel 26 in which the periphery of the segmental 30 disk 22 is adapted to extend and to have such portion of the block provided with the upstanding stationary pointer or index adapted to coöperate with the graduations 35 23 on the disk 22.

45 In order that the depth of the cut may be controlled or limited, I find it of advantage to have threaded vertically through the heads 27 of the saw guides 17 the screws 28, the lower extremities of which being adapted to contact with the upper ends of the 50 posts 12 and operating in a manner which is believed to be self-evident.

It often occurs in practice that it is especially desirable to maintain the saw in an 55 elevated or lifted position and, as herein disclosed, I provide for this purpose a spring-controlled latch 29 suitably secured to an outer face of each of the posts 12 and having an extremity thereof provided with an 60 inwardly directed pin 30 adapted to normally engage a recess or pocket 30^a formed in the post 17 adjacent the lower extremity thereof.

The controlling spring 31, as herein 65 disclosed, is disposed about the elongated mem-

ber 32 normally projected through the opposite extremity of the latch 30 and having its outer extremity adjustably engaged by the stop 33, herein shown as a conventional nut in threaded engagement with such member, which serves as a means to positively hold the latch in such position as to maintain the inwardly directed pin thereof in retracted position.

From the foregoing description, it is 75 thought to be obvious that a miter box constructed in accordance with my invention is of an extremely simple and comparatively inexpensive nature and is particularly well adapted for use by reason of the convenience 80 and facility with which it may be assembled and by reason of the effectiveness with which it performs its functions, and it will also be obvious that my invention is susceptible of some change and modification 85 without material departure from the principles and spirit thereof and for this reason I do not wish to be understood as limiting myself to the precise arrangement and formation of the several parts herein shown in 90 carrying out my invention in practice.

I claim:

1. A device of the character described comprising a work table, a segmental member projecting forwardly therefrom, a block 95 positioned below the segmental member, the rear face of said block being provided with an upstanding angular arm overlying the upper face of the segmental member and affording a suspending means for the block and permitting the same to be moved independently of the segmental member, a bar mounted for swinging movement on said work table and capable of axial rotation, said bar being also rotatably mounted in 100 the upper extremity of the angular arm of the block, and locking means carried by the block coacting with the segmental member for maintaining the block in different 105 adjustments relative to the segmental member.

2. A device of the character described comprising a work table, a segmental member projecting forwardly therefrom, a block 115 positioned below the segmental member, the rear face of said block being provided with an upstanding angular arm overlying the upper face of the segmental member and affording a suspending means for the block 120 and permitting the same to be moved independently of the segmental member, a bar mounted for swinging movement on said work table and capable of axial rotation, said bar being also rotatably mounted in the 125 upper extremity of the angular arm of the block, and locking means carried by the block coacting with the segmental member for maintaining the block in different 130 adjustments relative to the segmental member, said block being also provided with an up-

standing arm overlying the forward face of the segmental member and serving to maintain the block against movement transversely of the segmental member.

- 5 3. A device of the character described comprising a work table, a segmental member projecting forwardly therefrom, a block positioned below the segmental member, the rear face of said block being provided with
- 10 an upstanding angular arm overlying the upper face of the segmental member and affording a suspending means for the block and permitting the same to be moved independently of the segmental member, a bar
- 15 mounted for swinging movement on said work table and capable of axial rotation,

said bar being also rotatably mounted in the upper extremity of the angular bar of the block, locking means carried by the block coacting with the segmental member for 20 maintaining the block in different adjustments relative to the segmental member, and coacting means carried by the bar and the block for holding the bar against axial rotation.

25 In testimony whereof I hereunto affix my signature in the presence of two witnesses.

EARL ROY FOUST.
